UNITED STATES PATENT OFFICE.

GILPIN MOORE, OF MOLINE, ILLINOIS, ASSIGNOR TO DEERE & COMPANY,
OF SAME PLACE.

BEAM-COUPING FOR CULTIVATORS.

SPECIFICATION forming part of Letters Patent No. 357,727, dated February 15, 1887.

Application filed August 16, 1886. Serial No. 211,063. (No model.)

To all whom it may concern:

Be it known that I, GILPIN MOORE, residing at Moline, in the county of Rock Island and State of Illinois, and a citizen of the United States, have invented a new and useful Improvement in Beam - Couplings for Cultivators, of which the following is a full description, reference being had to the accompanying drawings, in which—

10 Figure 1 is a side elevation; Fig. 2, a top or plan view; Fig. 3, a vertical longitudinal section; Fig. 4, a detail showing one section or half of the vertical sleeve; Fig. 5, a detail showing the other half or section of the vertical sleeve; Fig. 6, a cross-section through the sleeve and its clamping-bolt; Fig. 7, a detail showing the clamping devices of the pipe-box disconnected; Fig. 8, a side elevation of the hand wheel or nut of the pipe-box clamp; Fig. 9, a 15 front side elevation of one of the blocks of the pipe-box clamp.

The objects of this invention are to improve the construction and operation of the vertical spindle which forms the pivot for the lateral swing of the beam, and to improve the means for adjusting the height of the forward end of the beam to produce the required running depth of the shovels, to improve the means for changing the distance between the shovel-gangs for the width of row, and to improve the construction and operation of the coupling as a whole; and its nature consists in the several parts and combination of parts, hereinafter described, and pointed out in the claims as new.

20 In the drawings, A represents a plate or fin, to be attached to the forward end of the beam, as usual, by bolts passing through the holes ab.

B is a head formed or cast with the plate A, and extending above and below the plate, and, 25 as shown, the upper part of the head has an arm or extension, B', with a slot or opening, b', for connection with the lifting - spring. (Not shown.)

C represents ears, one at each end of the head B, each ear having a hole with a tapering part, c, which ears C form the bearings for the vertical sleeve.

D represents heads, each having its inner face formed with a taper, d, to fit the taper c 30 of the ear C.

E represents the sections or halves forming the vertical sleeve, each section or half having at the end a lip, e, and one section having on its exterior face a spline or rib, e'. The head D and the sleeve-sections are cast or formed together, as shown in Figs. 4 and 5, and the lip e of one sleeve-section enters the head D of the other sleeve-section when the parts are together, as shown in Fig. 3.

F is a clamping-bolt for drawing the sleeve-sections endwise. When in place, the bolt passes through the sleeve-sections longitudinally, and has on its screw-threaded end a thumb or other nut, f, by which it can be made to draw the taper d of the heads D against the taper e of the bearings C to compensate for wear, and, as shown, the bolt F is held against side movement by the lips e of the sections E, which bear against the bolt on opposite sides when the parts are together, as shown in Fig. 3, and these lips also hold the half-sections together and against spreading at the ends by entering the lips between the bolt F and the wall of the head D.

G is a yoke, one end, g, of which is provided with a hole for the passage of the vertical sleeve E, the hole for the sleeve having, in line with the spline e', a groove or recess to receive the spline, and at the center of the closed end of the yoke is a hole, g', for the passage of a screw-threaded stem or bolt, which hole, as shown, is square for a part of the distance to receive the square head of the bolt and round the balance of the distance for the stem of the bolt.

H is a block fitting between the arms of the yoke, and located when the parts are together to have one face in contact with the halves of the sleeve E, the contact-faces of the block having a semicircular groove to receive the sleeve, and the opposite face of the block H is grooved transversely to fit the pipe-box.

I is a head or block having side wings or extensions, i, with the spaces i' between them for the passage of the closed end of the yoke G, and the ends of the wings i have a semicircular groove to fit the pipe-box. This head or block I has a central hole for the passage of the stem of the clamping-bolt.

J is a clamping-bolt, the square head of which

fits the square portion of the hole in the yoke G, and the stem of which is screw-threaded and passes through the hole therefor in the yoke G and head or block I.

5 K is a nut for the bolt J, and having connected therewith by radiating arms the rim K', formed of balls and connecting-bars to furnish a hold for the hand in turning on or off the nut.

L is the pipe-box, having a circular longitudinal hole for the passage of the spindle.

The parts are brought together by passing the sleeve E through the opening or hole therefor in the open end g of the yoke, the spline e' entering the opening therefor in the ends g, so as to lock the sleeve to the yoke against lateral turning, except when the two turn together, and at the same time leaving the yoke free to be raised and lowered on the sleeve. The bolt J is passed through the opening therefor in the yoke G, to have its stem receive the head or block I, which is slipped thereover for the yoke G to enter the opening or slot i' between the wings i. The nut K is screwed onto the stem J back of the head I, and the head H is slipped into place between the arms of the yoke G in contact with the sleeve E, which forms an opening between the blocks H I for the pipe-box, which is slipped into such opening and locked by forcing the block I forward by the hand-nut K K', which firmly clamps the coupling onto the pipe-box.

In use the coupling is adjusted on the sleeve E to raise and lower the forward end of the plow-beam by loosening the hand-nut K K' sufficiently to release the bite of the block H on the sleeve E and allow the sleeve to be raised or lowered in the yoke G to the extent required for the adjustment of the running depth, and when properly adjusted the parts are locked by force-

ing the block H into biting contact with the sleeve E. The coupling is adjusted laterally on the pipe-box L to widen or narrow the distance between the gangs by loosening the hand-nut K K' sufficiently to release the clasp of the blocks H I on the pipe-box and allow the lateral movement of the coupling on the pipe-box L, and when the adjustment desired is attained the blocks H I are tightened on the pipe-box L by turning down the hand-nut K K'. The lateral swing of the beam produces more or less wear of the sleeve-heads D in the bearings C, and the conical shape of the contact-faces of the heads and bearings through the draw of the rod F takes up the wear between the heads and the bearings by simply turning the nut f to draw the taper d of the heads D into contact with the taper c of the bearings C, thus enabling the sleeve to be used until worn out without becoming loose and impaired in its workings by reason of looseness.

What I claim as new, and desire to secure by Letters Patent, is—

1. The plate A B, provided with bearings C, each with a taper, c, in combination with the sleeve E, formed of two halves or sections, each having a head, D, with a taper, d, and draw-bolt F, for taking up the wear, substantially as specified.

2. The sleeve E, formed of two halves or sections, each having a head, D, with a taper, d, and the bearings C, in combination with the yoke G, and the clamping block H, for adjusting and locking the yoke on the sleeve, substantially as specified.

GILPIN MOORE.
